UNITED STATES PATENT OFFICE.

GERTRUDE HALL, OF NEW YORK, N. Y.

DESIGN FOR A DOLL.

Application filed April 25, 1924. Serial No. 9,394. Term of patent 14 years.

To all whom it may concern:

Be it known that I, GERTRUDE HALL, a citizen of the United States of America, residing in the city, county, and State of New York, have invented a new, original, and ornamental Design for Doll, of which the following is a specification, reference being had to the drawing, forming a part thereof.

In the drawing,
Figure 1 is a front perspective view of my new doll, and
Figure 2 is a side view thereof.

I claim:
The ornamental design for a doll substantially as shown.

GERTRUDE HALL.
